UNITED STATES PATENT OFFICE

154,924

DESIGN FOR A LAVATORY CABINET

Fred E. Huss, Toledo, and George C. Shepard,
Sugar Ridge, Ohio

Application June 19, 1947, Serial No. 139,820

Term of patent 3½ years

(Cl. D4—2)

To all whom it may concern:

Be it known that we, Fred E. Huss and George C. Shepard, citizens of the United States, and residents of Toledo, in the county of Lucas and State of Ohio, and of Sugar Ridge, in the county of Wood and State of Ohio, respectively, have invented a new, original, and ornamental Design for a Lavatory Cabinet, of which the following is a specification, reference being had to the accompanying drawings, forming a part thereof.

In the drawings Figure 1 is a perspective view of a lavatory cabinet embodying our design; Figure 2 is a front elevation; Figure 3 is a side view taken from the left of Figures 1 and 2; and Figure 4 is a top view. The right side of Figures 1 and 2 not shown in the drawings is a plain surface.

The dominant features of the design reside in those portions shown in full lines.

We claim:

The ornamental design for a lavatory cabinet, substantially as shown and described.

FRED E. HUSS.

GEORGE C. SHEPARD.
